UNITED STATES PATENT OFFICE.

ROLAND E. HILL, OF DECATUR, ILLINOIS, ASSIGNOR TO WILLIAMS SEALING CORPORATION, OF DECATUR, ILLINOIS, A CORPORATION OF ILLINOIS.

CAPPING DEVICE.

Application filed November 6, 1924. Serial No. 748,187.

This invention relates generally to tools or devices for applying and securing caps or closures to bottles, jugs, cans and similar containers, and more particularly to a hand 5 operated tool or device for applying and securing a cap comprising a locking lever which must be thrown down to secure the cap upon the mouth of the bottle neck or can nozzle, such form of cap being shown in the 10 Williams Patent No. 1,108,959, September 1, 1914.

The object of the present invention is to provide a simple form of tool which will combine the means for properly gripping the 15 can nozzle or bottle neck, with the cap thereon, with the lever tripping means arranged in such a manner that one hand which actuates the gripping means can also be employed to operate the lever tripping means, 20 and this with ease and rapidity without releasing the hold of the device upon the can nozzle or bottle neck.

With this object in view, the invention consists in providing a suitable frame, carrying a pair of gripping jaws and levers for operating the same, a cap receiving chuck head centrally disposed with reference to the said jaws and movable vertically with reference thereto and a lever tripping finger 30 having its inner end resting upon the front side of the head, its outer end being provided with a pinion which is engaged by a toothed hand lever for swinging the finger to turn down the cap lever, said finger being returned to its normal position by means of 35 a spring.

The invention consists also in the various details of construction and in the manner of combining or arranging the same, all of 40 which will be more fully described herein-after and then pointed out in the appended claims.

In the drawings forming a part of this specification.

Figure 1 is a face view of the device applied to a bottle neck or can nozzle ready for operation of the tripping finger;

Figure 2 is a view showing the finger in its tripped position and the cap locked upon the bottle neck or can nozzle;

Figure 3 is a section on the line 3-3 of Figure 1;

Figure 4 is a section on the line 4-4 of Figure 2;

Figure 5 is a detail view of the bracket

detached from its frame with the tripping finger arranged therein and

Figure 6 is a view of the device with the front side of the frame removed.

In constructing a tool in accordance with my invention I employ a frame 10 preferably composed of two parallel spaced plates and to the opposite ends of this frame I pivot the outwardly extending levers 11 at the points 12 and the inner ends of these levers are pivotally connected at 13 to the fins or ribs 14 of the posts 15 which work between the plates of the frame. These posts 15 have the gripping jaws 16 attached to their lower ends, said jaws being shaped to grip the can nozzle or bottle neck just below the outwardly extending shoulder or bead, these jaws moving laterally toward and away from each other through the movement of the levers 11. The jaws are separated when the handles are moved upwardly and forced towards each other to grip the can nozzle or bottle neck when the levers are separated or thrown downwardly. It will be noted that the fins or ribs are slotted where they are pivotally connected to the ends of the levers in order to permit the lateral movement of said jaws and also a definite amount of vertical movement with reference to the frame.

Stop pins 17 are attached to each of the posts 15 to limit the closing movement of the jaws. The frame plates are cut away centrally along the lower edge as shown at 10^a to receive a cap receiving chuck 18, the lower face of the chuck being recessed to receive the cap 19 therein. The chuck head is formed with an upwardly extending portion 18^a which is preferably positioned between the inwardly pressed tongue portions 10^b of the frame plates and this upwardly extending portion is bored to receive a pin 20 extending downwardly from the center of a cross piece 21 in which are fitted the hooked ends of the fins or extensions of the posts.

The chuck head is formed with an annular groove 22 into which fits the positioning lugs 23 in order to unite the head with the frame so that said head and frame move in unison. The front side of the chuck head is formed with a horizontal recess 24 and at the center of the front side there is produced a vertical notch 25.

Connected to the forward face of the front plate at one side thereof is a bracket 26

mounted in this bracket is the cap lever tripping finger 27 angled at its inner end as shown at 27^a, said inner end normally extending across the front side of the chuck head and resting in the recess 24. Surrounding the spindle portion of the finger is a coil spring 28, one end of which is connected to the finger and the other to the bracket, the purpose of this spring being to normally hold the inner end of the finger in the recess in the side of the chuck head and to return the same to this position after the said tripping finger has been operated to press down the lever 19^a of the cap, this lever standing upright before being locked and resting in the vertical notch 25 of the chuck head.

The angled end 27^a of the tripping finger is turned down through the arc of a circle carrying with it the cap lever 19^a when the capping operation is being carried out and in order to accomplish this operation I provide a pinion 29 upon the outer end of the spindle of the tripping finger, which pinion is engaged by the toothed end 30^a of the pivoted lever 30, this lever being pivoted upon the outer side of the bracket as most clearly shown and its outer end placed for convenient manipulation by the thumb of the hand gripping the right hand lever 11.

In operation the cap 19 is placed upon the mouth of the bottle neck or can nozzle and the tool is then placed over the same, the cap fitting into the recessed lower face of the chuck head and at the same time that the chuck head is forced downwardly to apply downward pressure upon the cap, the jaws are forced inwardly, gripping the neck of the bottle or nozzle of the can just below the external annular shoulder or bead and the jaws grip the nozzle slightly in advance of the final downward movement of the chuck head.

The parts are so proportioned and shaped that these jaws will support the outer end of the nozzle while the cap is pressed into close contact therewith and at this time the cap lever 19^a is extending upwardly in advance of the inner end 27^a of the tripping finger, resting in the vertical notch 25 which permits the proper positioning of the cap with the lever in the chuck head. The tripping finger is then rotated by pressing the thumb against the end of the lever 30, throwing said end rearwardly and the end of this lever being toothed, engages the pinion upon the outer end of the tripping finger, whereby said finger is rotated or swung through the arc of a circle, carrying with it the cap fastening lever 19^a. The moment the operation is completed, the thumb pressure is released and the spring returns the tripping finger to its normal position and at the same time the hand levers 11 are thrown up sufficiently to release the grip of the jaws.

It will be noted that the frame and chuck head are moved vertically with reference to the jaws at the same time that the jaws are moved toward and away from each other and through the same actuating means, 70 namely, the hand levers.

The lever tripping finger mechanism is so arranged that it does not interfere in the least with the cap forcing and neck or nozzle gripping operations and is quickly and 75 easily operated by the thumb of the same hand which actuates one of the operating levers.

It will thus be seen that I provide an exceedingly simple and highly efficient hand operated tool for fastening the particular type of bottle cap to the can nozzle or bottle neck without injury to the nozzle or can and at the same time employing proper pressure. 80

What I claim is:—

1. The combination with a pair of jaws and means for moving the said jaws laterally, of a chuck head vertically movable by the jaw operating means, and a cap lever tripping means movable with the chuck head 90 and operable independently thereof.

2. The combination with a pair of jaws, and means for moving the same laterally toward and away from each other, of a chuck head movable vertically by the jaw operating 95 means, a lever tripping finger arranged in connection with said chuck head and means for operating the same.

3. The combination with a pair of jaws and means for moving the same laterally, a 100 centrally disposed chuck head movable vertically by the jaw operating means, a lever tripping finger having its end arranged across the front face of said chuck head and means for moving said finger.

4. The combination with a pair of jaws, and means for moving the same laterally toward and away from each other, of a centrally disposed chuck head movable vertically with reference to the jaws by the jaw 110 operating means, a lever tripping finger arranged in connection with said chuck head and having its inner end extending across the front side of said head, a pinion on the outer end of said tripping finger, and a pivoted segment engaging said pinion for moving said finger. 115

5. The combination with a frame carrying a chuck head and a pair of jaws and means for operating said jaws and head, a tripping finger mounted on said frame and having its inner end extending across the front side of said chuck, a pinion on the outer end of said finger, and a pivoted toothed segment engaging said pinion to operate the finger. 120

6. The combination with a frame carrying a pair of jaws, operating levers operatively connected with said jaws and a centrally disposed chuck head, of a bracket carried by the frame, a tripping finger mounted in said 125 frame.

bracket, the inner end of said finger resting in a recess in the front side of the head, a pinion on the outer end of said finger and a toothed lever for engaging said pinion and 5 operating said finger.

7. The combination with a frame carrying a pair of jaws, operating levers pivotally connected with said jaws and adapted to actuate the same, and a centrally disposed 10 chuck head, the front side of said head being notched and recessed, of a bracket attached to said frame, a tripping finger mounted in said bracket, a toothed lever pivoted thereto, a pinion on the outer end 15 of said tripping finger, the inner end of said finger resting in the recess in the front face of said chuck head and means for normally holding said finger in this position.

8. The combination with a frame, carrying

a pair of jaws, operating levers pivotally 20 connected with said jaws and adapted to actuate the same, and a centrally disposed chuck head, having its front side horizontally recessed and vertically notched, of a bracket attached to said frame, a lever tripping finger mounted therein, the outer end 25 of said finger having a pinion thereon, a toothed lever pivoted to said bracket and engaging said pinion, the inner end of said finger normally resting in the recess in the 30 side of said chuck head and a spring surrounding said finger for holding said finger in this position and returning the same thereto when moved by the toothed lever.

In testimony whereof, I hereunto affix my 35 signature.

ROLAND E. HILL.
